Primary Examiner — Patricia A Palasik*(74) Attorney, Agent, or Firm* — Donald J. Lecher; Butzel Long**CLAIM**

The ornamental design for a UV-light disinfection robot base, as shown and described.

DESCRIPTION

FIG. 1 shows a top left-side front perspective view of the UV-light disinfection robot base of our new design, disclaiming a lighting tower assembly and a top optical assembly of a UV-light disinfection robot mounted on a distal end thereof;

FIG. 2 shows a front elevation view thereof;

FIG. 3 shows a right-side elevation view thereof;

FIG. 4 shows a rear elevation view thereof;

FIG. 5 shows a left-side elevation view thereof;

FIG. 6 shows a top plan view thereof;

FIG. 7 shows a top right-side rear perspective view thereof;

FIG. 8 shows a bottom left-side front perspective view of the UV-light disinfection robot base, opposite that of FIG. 7, disclaiming the lighting tower assembly and the top optical assembly mounted on the distal end thereof, wherein a central region of a lower portion of the undercarriage of the UV-light disinfection robot base defined by a dash-dot-dash line is disclaimed; and,

FIG. 9 shows a bottom right-side rear perspective view of the UV-light disinfection robot base opposite that of FIG. 1, the embodiment disclaiming the lighting tower assembly and the top optical assembly mounted on the distal end thereof, wherein a central region of a lower portion of the undercarriage of the UV-light disinfection robot base defined by a dash-dot-dash line is disclaimed.

The broken or evenly-dashed lines are included to show structure of the robot that form no part of the claimed design.
